DESIGN FOR A COMBINED EVENING AND STREET DRESS

Samuel Chapman, New York, N. Y.

Application October 12, 1938, Serial No. 80,391

Term of patent 3½ years

To all whom it may concern:

Be it known that I, Samuel Chapman, a citizen of the United States of America, residing in the city of New York, county of New York, and State of New York, have invented a new, original, and ornamental Design for a Combined Evening and Street Dress, of which the following is a specification, reference being had to the accompanying drawing, forming part thereof.

Fig. 1 is a front view of a combined evening and street dress, showing my new design.

Fig. 2 is a rear view thereof.

Fig. 3 is a front view of the dress with the outerskirt removed.

Fig. 4 is a rear view of Fig. 3.

I claim:

The ornamental design for a combined evening and street dress, substantially as shown.

SAMUEL CHAPMAN.
